(57) **CLAIM**

The ornamental design for a bottle, as shown and described.

DESCRIPTION

FIG. 1 is a top rear perspective view of a bottle showing a first embodiment of the design.

FIG. 2 is a front view of thereof.

FIG. 3 is a rear view thereof.

FIG. 4 is a right side view thereof.

FIG. 5 is a left side view thereof.

FIG. 6 is a top view thereof.

FIG. 7 is a bottom view thereof.

FIG. 8 is a top rear perspective view of a bottle showing a second embodiment of the design.

FIG. 9 is a front view thereof.

FIG. 10 is a rear view thereof.

FIG. 11 is a right side view thereof.

FIG. 12 is a left side view thereof.

FIG. 13 is a top view thereof; and,

FIG. 14 is a bottom view thereof.

The broken lines in FIGS. 1, 6, 7, 8, 13, and 14 define the bounds of the claimed design and form no part thereof.

1 Claim, 8 Drawing Sheets
